Specification for Design.

Patented Aug. 29, 1922.

Application filed March 3, 1922. Serial No. 993. Term of patent 3½ years.

To all whom it may concern:

Be it known that I, EMIL FUCHS, a subject of the King of England, residing at New York city, in the county of New York and State of New York, have invented a new, original, and ornamental Design for a Spoon, of which the following is a specification, reference being had to the accompanying drawing, forming part thereof.

Figure 1 shows the back of a spoon, showing my new design.

Figure 2 shows the front of the spoon; and

Figure 3 is an edge view of the spoon.

I claim:

The ornamental design for a spoon, as shown.

EMIL FUCHS.
